UNITED STATES PATENT OFFICE.

ALFRED MILLER, OF DESSAU IN ANHALT, GERMANY, ASSIGNOR TO I. G. FARBEN-INDUSTRIE AKTIENGESELLSCHAFT, OF FRANKFORT-ON-THE-MAIN, GERMANY.

PROCESS OF PHOTOGRAPHIC COPYING BY THE REFLECTION METHOD.

Application filed March 26, 1926, Serial No. 97,757, and in Germany November 14, 1924.

This invention relates to a process for producing copies by the "reflection photography" process.

Known processes of this kind have for 5 their object the production of a negative to be used either as such or as a preliminary copy for subsequent printing. The player-type, Arnhard- and book-photo-printing-processes depend upon the use of a silver 10 halide emulsion. Ullmann has proposed the use of a chromated colloid layer or of double salts of iron and silver; Winkler recommends a colloid layer in conjunction with an iron salt to which may be added a manganese or 15 uranium salt, whilst Kögel's process depends upon the use of diazo compounds.

In all the methods hitherto suggested of producing copies by this kind of process it is necessary to work with very thin layers, in 20 order that the possibility of fogging may be restricted, but in spite of this precaution it is not possible to obtain negatives free from objections without a very considerable amount of practice and without depending 25 upon factors the action of which cannot be controlled.

As distinguished from the known processes, by the present invention it is possible to obtain easily negatives which are rich in 30 contrast and are free from fog. The printing forms obtained yield clear prints rich in contrast. This result is attained by applying the treatment which follows the exposure, for example the colouring for building up 35 the negative only to the surface of the sensitive layer instead of treating the whole layer as has hitherto been usual. This method has advantages over the known methods. Thus, whilst in known methods only very thin layers 40 are permissible, it is possible in the method according to the invention to vary the thickness of the layer within wide limits, from 0.001 mm. up to 0.1 mm. or more, since for producing the picture there are utilized 45 only the alterations which occur on the surface of the layer. Moreover, the limits within which the exposure may be varied, particularly when thicker layers are used, are much greater than in known processes, and 50 finally the tendency towards appearance of fog is satisfactorily avoided.

The methods hitherto proposed, whether depending upon the use of silver halide emulsions and subsequent chemical development, or upon the use of chromated colloids,

iron salts, etc., suffer from the defect that in the treatment which follows the exposure, the layer is affected throughout its whole thickness, and therefore the effects of the treatment extend to the portion of the layer 60 which is immediately adjacent to the support on which the layer is carried, that is to say, to the portion which during the exposure has received so much incident light that the quantity of reflected light reaching 65 this portion is unable to produce the required effect. In the known processes hereinbefore referred to, efforts were made to counteract this defect at the expense of the contrast and with a restriction in the limits of the exposure, by using very thin layers. As compared with these processes, the new process is within practical limits independent of the thickness of the layer, since only the surface of the layer comes into consideration 70 for the formation of the picture, and the exposure of the parts of the layer which adjoin the support are without influence on the copy or printing form obtained.

It is evident that during the exposure, the 80 greatest difference between the action of incident and of reflected light occurs to the surface of the copying layer, and this is equally true in the case of an unusually thick layer. Whilst with the processes used up to 85 now the use of thick layers, in which the sensitizer is distributed throughout the layer and is thus present in the region adjacent to the support, produces a general illumination of this region which impairs the result obtained and reduces the contrast by its tendency to produce a uniform effect over the whole layer, a process which depends only 90 on the action of light on the surface of the layer renders possible and favours the production of sharp contrasts and pure lights, since the region of the layer adjoining the support is unaffected by this treatment.

It is to be understood that during exposure fog is produced in the new process as 100 well as in all the processes known up to now, because the sensitizer incorporated in the colloid layer is altered by the action of light throughout the whole thickness of the layer, but since the fog thus produced is made visible by the after treatment only, the appearance 105 of fog on the copy can be avoided by a suitable modification of the after treatment. This modification consists in restricting the after treatment solely to the surface of the 110

layer and avoiding the utilization of the lower zones of the colloid layer which are adjacent to the support for building up the picture. The general principle of the present invention may be determined as follows: Copying by the reflection method without caring for possible fogging, neither by diminishing the thickness of the light sensitive layer nor by other measures, and 10 restricting the after treatment by which the picture is built up merely to the surface of the layer. It is obvious that this general principle may be applied to all light sensitive layers whether they be sensitized by 15 silver halides, chromium salts, iron salts or other sensitizers, whenever it is possible to strictly limit the after treatment to the surface of the layer and to exclude the lower zones of the layer from building up the 20 picture. Since this is really feasible the principle is capable of various applications, as will hereinafter appear.

By the process according to the invention it is possible to produce a printing surface 25 directly by exposure by reflection. This may, for example, be carried out in the following manner:

A plate or film of transparent material, preferably dyed in order that it may also 30 serve as a light filter, is coated with a colloid layer, which is then sensitized by means of a solution of bichromate, which may contain in addition a catalyst, such as a salt of manganese or of copper, and is finally dried. It 35 is then placed in the printing frame with the original to be copied, the colloid layer being adjacent to the original, which may be for instance a black drawing on a white ground, and the exposure is made from the back 40 through the support. Thus the bichromatized colloid acquires a selective faculty for retaining pigments brought thereon. Pigments may be distributed over the surface of the colloid in the form of a fine powder; 45 preferably the said powder may be dispersed in a fatty medium so as to form a fatty ink well known in the printing art. After washing, drying and moistening with a mixture of water and glycerine, prints may be 50 made with a fatty ink from the flat printing surface so obtained, whereby a right handed picture is produced in white upon a black ground i. e., the right hand side of the object to be represented corresponds to the right 55 hand side of the picture.

When using films, it is advantageous to apply a so-called "non-curling" layer to the back of the film in order to equalize the strains which the sensitive layers exert on 60 the support, particularly when the sensitive layer is relatively thick. These non-curling layers have not been used in the known processes, because the treatment of the exposed layer necessitated the immersion of 65 the whole picture in the bath, and the non-

curling layer would be affected by this treatment, so that the manipulation of the film would be rendered more difficult, and the quality of the picture would be inferior. In the process according to the invention, however, the non-curling layer is not affected, since the treatment after exposure is restricted to the surface of the sensitive layer. For the same reason the invention renders it possible to use a layer on the back of the 70 support for retouching, an advantage which is very essential when a negative is concerned.

If it is desired to produce a number of positives from the picture, a print may be 75 made on zinc from the printing surface and may be reversed in known manner and printed in an offset printed machine. A print may also be made from the printing surface on a photolithographic transfer paper and this may be transferred on to zinc, again reversed in known manner, and prints may be taken directly from the zinc.

The printing surface may also be used as a negative, for which purpose it is soaked in water after having been inked with a fatty ink, after which it is dried, and may advantageously be sprinkled with bronze-powder in order to strengthen the covering power. It may then be provided with a very thin coating of lacquer and in this condition may be retouched as desired.

Negatives may also be made in the manner of photolithographic copying by aid of fatty ink. For this purpose the sensitive layer consisting of a colloid adapted to swell is inked with a fatty ink after exposure, and is developed by washing. The procedure also may follow that of albumen-printing on zinc by using a colloid layer 85 which is soluble in water. To the water there may be added an agent which promotes development such as lactic acid, acetic acid.

Copies may also be made by spraying a 90 hygroscopic colloid layer with fine powder after the layer has been exposed by the reflection method and breathed upon or similarly treated.

As colloids there may be used gelatine, 95 glue, gum arabic, sugar and like substances sensitized for instance by chromates, iron salts, uranium salts.

Figs. 1 and 2 of the accompanying drawings represent sections on an enlarged scale 100 through films embodying the present invention. Referring to Fig. 1, 1 is a support of celluloid or other suitable material and 2 is a layer of a colloid sensitized to light by bichromates or other light-sensitive salts. On the surface of layer 2 deposits 3 of a finely powdered pigment are retained at the areas affected by light during exposure. Fig. 2 shows deposits 4 of a finely powdered pigment, which has previously been dispersed 105

in a fatty medium, retained at the areas affected by light during exposure, 1 and 2 being the support and the sensitized colloid, respectively.

- 5 If silver halide emulsions are used, on the surface of the layer a selective deposition of particles of any metal or metal compound from a supersaturated solution thereof must take place. Such a selective deposition is 10 known as physical development; it also occurs when the picture developed chemically is intensified by a physical method.

What I claim is,—

- 15 1. A process for producing copies by the reflection method wherein the treatment of the sensitized colloid layer after exposure for the purpose of building up the picture is restricted to the surface of said layer.

- 20 2. A process for producing copies by the reflection method which consists in treating after exposure the sensitized colloid layer carried on a transparent support in such a manner that the photochemical alterations solely in the surface of said layer are utilized for building up the picture.

- 25 3. A process for producing copies by the reflection method which consists in treating after exposure the sensitized colloid layer carried on a transparent flexible support, in such a manner that the photochemical alterations solely in the surface of said layer are utilized for building up the picture.

- 30 4. A process for producing copies by the reflection method which consists in treating after exposure the sensitized colloid layer, carried on a transparent flexible support provided on the back with a colloid layer, in such a manner that the photochemical alterations solely in the surface of the first mentioned layer are utilized for building up the picture.

- 35 5. A process for producing copies by the reflection method according to claim 4 which consists in treating after exposure the sensi-

tized colloid layer which is adapted to swell 45 in such a manner that the photochemical alterations solely in the surface of the layer are utilized for building up the picture.

6. A process for producing copies by the reflection method according to claim 4 which 50 comprises moistening the surface of the sensitized colloid layer and distributing thereon a fine pigment.

7. A process for producing copies by the reflection method according to claim 4 which 55 consists in distributing over the surface of the sensitized colloid layer pigment dispersed in a fatty medium and developing the colloid layer with water.

8. A process for producing copies by the reflection method according to claim 4, the development of said colloid layer being carried out with water containing an agent which aids the developing of the layer.

9. A process for producing copies by the reflection method, according to claim 4, the development of said colloid layer being carried out with water containing an organic acid.

10. A process for producing copies by the reflection method, according to claim 4, the said colloid layer after having been exposed being inked with a fine pigment dispersed in a fatty medium and spread with a pigment.

11. A process for producing copies by the reflection method according to claim 4, the said colloid layer being converted after exposure into a printing surface in the manner of phototypy.

12. A process for producing copies by the reflection method, according to claim 4, the said colloid layer being converted after exposure into a flat printing surface by utilizing the swelling properties of the said colloid.

In testimony whereof I affix my signature.

ALFRED MILLER.
